BY

Thos. Hannan, ATTORNEY.

UNITED STATES PATENT OFFICE

MICHAEL HALEY, OF WEST BRANCH, MICHIGAN

ROPE FASTENER

Application filed March 29, 1929. Serial No. 350,913.

My invention relates to a new and useful improvement in a rope fastener and has for its object the provision of a device which may be mounted on a suitable support and which will afford means for easily and quickly and firmly securing the loose end of a rope thereto.

It is another object of the invention to provide a device of this class which will be simple in structure, economical of manufacture and highly efficient in use.

Other objects will appear hereinafter.

The invention consists in the combination and arrangement of parts hereinafter described and claimed.

The invention will be best understood by a reference to the accompanying drawings which form a part of this specification, and in which,

Fig. 1 is a perspective view of the invention showing it mounted.

Fig. 2 is a perspective view of the invention from a different angle.

Fig. 3 is a side elevational view of the invention.

Fig. 4 is a central sectional view of the invention.

The invention is preferably made from metal and the method of manufacture will be readily apparent to those skilled in the art, upon reading the within description. The device comprises an escutcheon plate 9 having openings 10 formed therein through which screws 11 may be projected for securing the fastener to a suitable support 12. Projecting outwardly from one end of plate 9 is a curved neck 13 having supports at its upper end and a ram's head having the outwardly projecting nose 14 and the horns

15 at opposite sides thereof. As shown in Fig. 3, the horns 15 are curved out of the normal plane of the neck 13. These horns are also curved to provide a pocket 16 adjacent the base and at the opposite side at the outer end a pocket 17. A rope drawn over one of the horns and brought forwardly of the neck 13 and thence around the other horn from the under side thereof and thence around the opposite horn again, may be securely locked in position on the support,

The rope which is fastened extends in the direction of the nose 14, this nose 14 serving to prevent lateral pulling on the rope. The pockets 16 and 17 serve as recesses in which the rope may be engaged and facilitate the clamping of the rope in firm position. Various hitches of rope may be made on the device since the four parts, comprising the nose, two horns and the neck are so arranged as to direction of projection and curvature as to provide the necessary recesses and curvatures at the desired points in making the various hitches. The simplicity of the invention is believed evident so that its economy of manufacture will be apparent.

The invention is especially adapted for fastening of clothes lines, guy ropes, awning lines, tow lines, stock halters, etc., and in view of the nature of the construction, is one which will prove labor saving as the hitches may be easily and quickly made.

While I have illustrated and described the preferred form of my invention, I do not wish to limit myself to the precise details of structure shown but desire to avail myself of such variations and modifications as come within the scope of the appended claims.

Having thus described my invention, what I claim as new and desire to secure by Letters Patent is:

1. A rope fastener of the class described comprising: a plate mounted on a supporting surface; a curved neck projecting outwardly from one end of said plate; a head mounted on the upper end of said neck a pair of lateral extensions on said head and an angularly turned forwardly projected portion on said head.

2. A rope fastener of the class described comprising: a plate mounted on a supporting surface; a curved neck projecting outwardly from one end of said plate; a head mounted on the upper end of said neck a pair of lateral extensions on said head and an angularly turned forwardly projected portion on said head, said lateral extensions being curved out of the normal plane of said neck and each having a plurality of pockets or curved recesses formed therein.

3. A rope fastener of the class described

comprising: a plate mounted on a supporting surface; a curved neck projecting outwardly from one end of said plate; a head mounted on the upper end of said neck a pair of lateral extensions on said head and an angularly turned forwardly projected portion on said head, said lateral extensions being curved out of the normal plane of said neck and each having a plurality of 10 pockets or curved recesses formed therein, the curvature of said neck being faced toward said plate.

In testimony whereof I have signed the foregoing specification.

15

MICHAEL HALEY.
